UNITED STATES PATENT OFFICE.

LARS MAGNUS ERICSSON, OF STOCKHOLM, SWEDEN, ASSIGNOR TO AKTIE-BOLAGET L. M. ERICSSON & CE., OF STOCKHOLM, SWEDEN.

SIGNALING-JACK FOR MULTIPLE-TELEPHONE EXCHANGES.

SPECIFICATION forming part of Letters Patent No. 729,560, dated June 2, 1903.

Application filed February 12, 1901. Serial No. 47,039. (No model.)

To all whom it may concern:

Be it known that I, LARS MAGNUS ERICSSON, manufacturer, a subject of the King of Sweden and Norway, and a resident of Thulegatan 5, Stockholm, in the Kingdom of Sweden, have invented certain new and useful Improvements in Signaling-Jacks for Multiple-Telephone Exchanges, (for which I have filed applications for patent in Sweden the 10 8th day of August, 1900, under No. 1,327/00; in Austria the 15th day of October, 1900; in Hungary the 17th day of October, 1900, under No. 14,527; in Great Britain the 24th day of December, 1900, under No. 23,610; in Norway the 24th day of December, 1900, under No. 13,351; in France the 31st day of December, 1900, under No. 295,175; in Russia the 26th day of August, [8th of September,] 1900, under No. 11,936; in Germany the 2d day of 15 20 January, 1901; in Belgium the 3d day of January, 1901, under No. 122,067; in Italy the 3d day of January, 1901, under No. 84/5, and in Spain the 4th day of January, 1901,) of which the following is a specification, reference being had therein to the accompanying 25 drawings.

This invention relates to signaling-jacks for multiple-telephone exchanges.

In the systems hitherto employed in multiple-telephone exchanges the testing device is usually so contrived that the line of a calling subscriber is indicated as engaged only after the insertion by the operator of a plug into the corresponding local jack. This often 30 gives rise to unpleasant complications, since connection may be made with the line of a calling subscriber elsewhere in the exchange before the operator has had time to indicate it as engaged.

40 The present invention has for its object to cause a subscriber's line to be indicated as engaged by the calling operation itself, this being accomplished by means of a combination of annunciator and local jack with an 45 electromagnet situated in an extension of the same and utilized also for indicating a call. This operation consequently is carried out in a different manner from that hitherto employed. The signaling or indicating part of the jack has 50 been placed at the forward end of the said

jack, being composed of a concentric enlargement of the ordinary jack-tube. This signaling part, which is movable longitudinally, slides forward as the calling-current traverses the electromagnet, the call being thereby indicated to the operator simultaneously with the formation of a larger inlet-aperture in the jack. 55

Figures 1 to 6 in the accompanying drawings illustrate the construction of this so-called "signaling-jack" as employed in parallel-jack systems. Fig. 1 is a section showing its position immediately after a call. Fig. 2 is a similar view showing its position on the insertion of the answering-plug. Figs. 3 and 4 60 are different side views of the signaling or indicating part proper. Fig. 5 is a section on the line A B of Fig. 1, taken between the jack and the jack-socket; and Fig. 6 is an end view. Fig. 7 is a diagrammatic view illustrating the mode of connecting the signaling-jack in a series system of jacks. Fig. 8 is a diagrammatic view illustrating its connection in a parallel-jack system in which some kind of relay is used for cutting out the signaling-electromagnet when connection is 65 made with a multiple jack. Fig. 9 is a plan of the guide-socket 4, showing recesses a a. 70

As will be seen by reference to Figs. 1 and 2 the outer frame of the signaling-jack is 80 composed of an iron tube 1. This is attached at its forward end to the securing-neck 2, which is threaded at its forward end to receive the securing-nut 3. The neck 2 supports in its interior the guide-socket 4 for the 85 plug. Between the said socket and neck is a concentric aperture, in which is located a tubular piece 5, which can move freely. The latter is provided with two prongs 15 and 16, passing through two recesses a a in the shoulder of the guide-socket 4. In the rear of this part the spring-jack is placed. This consists of the line-springs 31 and 32, the cutting-out spring 33 of the signaling-electromagnet, the cutting-out spring 34 of the relay-electromagnet, 90 the test-line spring 35, and the test-battery spring 36. In the free space at the side of the line-spring 31 is placed a slide 6, having two arms 13 and 14, in each of which is an insulating-piece 13^a 14^a, which under the 95 100

action of the spiral spring 7 tends to move in the direction of the guide-socket 4. Attached to the slide 6 is a metal band 8, extending outside the frame 1 to the rear end of the latter, 5 where it is retained in its normal position by the catch 9, the slide 6 being thereby kept from moving forward. Close behind the spring-jack the electromagnet 10 is located. The armature 11 of the latter is suspended in the 10 iron frame and provided with an angularly-projecting arm 12. When a calling-current traverses the electromagnet which is connected in a subscriber's circuit, the armature 11 is attracted, and the arm 12 consequently 15 moving upward releases the band from the catch 9. The slide 6 being then driven forward under the action of the spiral spring 7 forces the test-line spring 35 against the test-battery spring 36 by means of its two insulated prongs 13 and 14, at the same time breaking 20 the contact between the test-line spring 35 and the cutting-out spring 34 of the relay-electromagnet. The said prongs 13 and 14 at the same time are brought in contact with 25 the prongs 15 and 16 of the tubular piece 5, compelling the latter to advance from its previous concealed position, and thus indicate that a call has been made from the line in question. When the slide 6 advances, on its 30 release it effects a contact between the springs 37 and 38 on the rear piece by means of the metal band 8 and pin 17. These springs are connected in a local circuit, which, moreover, contains a battery and an indicator 24, Fig. 8, 35 or other visual signal, such as a glow-lamp or the like, common to a certain number of lines—for instance, to all lines in charge of one operator. When the answering-plug is inserted in the jack where a call-signal has 40 appeared, the signaling-tube 5 is pushed by the said plug into its concealed position. By means of the prongs 15 and 16 the slide 6 is then likewise forced back into its normal position, where it is retained by the catch 9. 45 In this operation the test-line spring 35 is released from the action of the slide; but as the plug forces the line-spring 32 slightly aside the latter by means of the insulation 18 will continue to hold the test-line spring 35 in 50 contact with the test-battery spring 36 as long as the plug remains in the jack.

The construction of the signaling-jack is the same whether it be used for series or parallel-jack systems, except that, as will be recognized by electricians, the relay device will be replaced in a series system with a spring normally in contact with the line-spring 32, but released from such contact when connection is made in the signaling-jack. 55

60 Fig. 8 illustrates the connection of the signaling-jack in a parallel-jack system. Like parts are indicated by like numerals to those used in Figs. 1 and 2.

In making connection in the local jack 19 65 the electromagnet-coil 10 is cut out by the plug, directly breaking the contact between

the springs 31 and 33. When connection is made in one of the multiple jacks 20, this cutting out of the electromagnet-coil 10 is effected by the closing of the current from the test-battery 21 through the test-spring of the jack, the test-line 27, and the relay-coil 22, the contact 23, located between one of the double-circuit branches 26, and the line-spring 31 in the signaling-jack being consequently broken. 70 If the local jack 19 in the present instance were to operate in the same manner as a multiple jack, the result would be that an immediate break would be caused by the relay in one of the line branches, this being due to 75 the fact, evident from the above description, that when a call is made the battery 21 will be connected with the test-line 27 through the springs 36 and 35. To avoid such a break, the relay-coil 22 is not directly connected 80 with the test-line 27, but with the jack-spring 34, which in the normal position of the jack is in contact with the test-line spring 35, while directly a call is made it is released from the 85 said contact. When connection has been 90 made in a multiple jack, the relay-coil 22 consequently is always in connection with the test-line 27, whereas in calling, as well as in connecting in the local jack, the relay-coil always becomes disconnected from the test-line. 95 By this construction the additional advantage is gained that the consumption of current becomes only one-half of what it would be in case the calling-subscriber's relay as 100 well were connected in the circuit while a connection lasts.

Fig. 7 also illustrates the construction of the signaling-jack in a multiple-jack system differing from Fig. 8 in representing an arrangement in series instead of in parallel. 105 In the arrangement in series cutting-out spring 34 of the relay-electromagnet becomes a spring 34, Fig. 7, in contact with line-spring 32 until connection is made in the signaling-jack by insertion of the plug, whereupon said 110 springs separate, thereby cutting out the signaling-electromagnet from the line branches. In other respects, as previously stated, the construction of the signaling-jack system is the same for series and parallel-jack systems. 115

24 denotes the above-mentioned indicator common to a certain number of lines. The test-battery 21 is the common battery.

There is evidently nothing to prevent the use of the signaling-jack in combination with other indicating devices—such as flaps or shutters, relays with glow-lamps, &c.—now commonly employed. The function of its electromagnet will then only be to accomplish the disconnection of the test-line from the relay-coil 22 and its connection with the test-battery when a call-signal is given. 120 125

Having now described my invention, what I claim as new, and desire to secure by Letters Patent, is—

1. In a signaling-jack for multiple-telephone exchanges, the combination of an elec- 130

tromagnet 10, its armature 11 having the projecting arm 12, a band 8, a catch 9 for normally retaining said band, springs 34, 35, 36, a slide 6 attached to said band, having two prongs 13, 14, to connect springs 35 and 36 and separate springs 34 and 35, a spring 7 for actuating said slide in one direction, a tubular piece 5 having prongs 15 and 16 and adapted to return said slide into normal position; whereby, upon energizing said magnet, its attracted armature will release band 8 from catch 9 and allow spring 7 to move slide 6 forward; substantially as described and shown.

2. In a signaling-jack for multiple-telephone exchanges the combination of an electromagnet, armature with projecting arm, spring-actuated slide having two arms carrying two insulating-arms to make contact between springs 35 and 36 and break contact between springs 35 and 34, a metal band connected with said slide, and a catch for normally retaining said band; the line-springs 31, 32, the cutting-out spring 33 of the signaling-magnet, the test-line spring 35, test-battery spring 36, and relay cutting-out spring 34; springs 37 and 38, a local battery and an indicator, in a local circuit; tubular piece 5 operated by said slide and having the prongs 15 and 16, and guide-socket 4 having the two recesses *aa* for reception of said prongs; substantially as described and shown.

3. In a signaling-jack for multiple-telephone exchanges the combination of an electromagnet, armature with projecting arm, spring-actuated slide having two arms carrying two insulating-contacts to make contact between springs 35 and 36 and break contact between springs 35 and 34, a metal band connected with said slide, and catch for normally retaining said band; the line-springs 31, 32, test-line spring 35, test-battery spring 36, springs 37, 38, a battery and an indicator, all connected in a local circuit, cutting-out spring 34 therefor, a tubular piece 5 operated by said slide and having the prongs 15 and

16, and guide-socket 4 having the two recesses *aa* for reception of said prongs; substantially as described and shown.

4. In a multiple-signaling jack, the combination of the securing-neck, the socket in which the plug is to be inserted and between, and concentric with, said neck and socket, a longitudinally-movable tube 5, having two prongs, a spring, and a slide operated in one direction by said tube and in the other by said spring and serving the two purposes of returning the slide into its normal position when the ordinarily-used plug is inserted and of indicating by its protruding end the fact of a call; substantially as described and shown.

5. A multiple-signaling jack composed of an electromagnet, an armature with projecting arm, a spring-actuated slide having two arms carrying two insulating-contacts to make contact between springs 35 and 36 and break contact between springs 34 and 35, a band connected with said slide, a catch for normally retaining said band, a securing-neck, a socket for insertion of the plug, a longitudinally-movable tube concentric with and between said neck and socket, in combination with a test-line spring 35, a relay device having a cut-out spring 34 normally in contact with said test-line spring, line-springs 31, 32, test-battery spring 36, springs 37, 38, all in a local circuit, the whole adapted to cut out the signaling-electromagnet by the movement of said slide, and also to indicate the engagement of a subscriber's line the moment the call is made; substantially as described and shown.

In witness whereof I have hereunto signed my name in the presence of two subscribing witnesses.

LARS MAGNUS ERICSSON.
